CLAIM

The ornamental design for an anti-loosening nut as shown and described.

DESCRIPTION

FIG. 1.1 is a perspective view of a anti-loosening nut;
 FIG. 1.2 is a front elevational view thereof;
 FIG. 1.3 is a rear elevational view thereof;
 FIG. 1.4 is a left elevational view thereof;
 FIG. 1.5 a right elevational view thereof;
 FIG. 1.6 a top elevational view thereof;
 FIG. 1.7 a bottom elevational view thereof;
 FIG. 1.8 a cross-sectional view thereof, taken along line 1.8-1.8 of FIG. 1.5; and

(Continued)

FIG. 1.9 is an exploded perspective view thereof, showing my design.
